ANTENNA SYSTEM

Wilhelm Moser and Hans Erich Paul, Berlin, Germany, assignors to Telefunken Gesellschaft für Drahtlose Telegraphie m. b. H., Berlin, Germany, a corporation of Germany

Application March 5, 1937, Serial No. 129,162
In Germany April 28, 1936

6 Claims. (Cl. 250—33)

Linear antennas are known whereby two conductors extending parallel to each other and fed in opposite phase surround each other alternately in certain sections whereby the total radiation is substantially in phase. The surrounding sections are in such known arrangements preferably of a length equal to one half wave length or shorter. Figure 1 shows such a known construction in which the cylindrical sections *a*, *b*, *c* surround the connector sections *d*, *e*, *f* coaxially. The line is so arranged that always a surrounding section is connected with the subsequent inner piece. Such an antenna may be fed, for instance, at the ends *g*, *h* across a high frequency transformer *i*. It is immaterial how the antenna structure is oriented in space whether horizontally, for instance, or vertically.

In cases where further electrical apparatus must be connected with the far end of the antenna with respect to the transmitter. It is impossible to arrange its connection lines parallel to the antenna or to otherwise connect them in the vicinity of the antenna since the radiation diagram of the antenna would thus be changed in an undesirable manner. For instance, it may be desired to supply power to an illumination bulb at the upper end of the antenna, or to have a further antenna placed thereabove of a different wave length and connected with another transmitter or with the same transmitter through a suitable energy line. This problem cannot be solved with the hitherto known forms of such antennas as far as we are aware. The present invention provides a construction by means of which the above problem is solved.

In accordance with the present invention a linear antenna radiating in equal phase is employed which consists of two oppositely fed conductors arranged parallel to each other, in a such manner known that the first conductor surrounds the second one and alternately, the second conductor surrounds the first one. The characteristic feature of the invention is hereby that the conductors enclose a continuous hollow space substantially shielded metallically at the sides for the high frequency.

A better understanding of the invention may be had by referring to the following detailed description which is accompanied by drawings wherein:

Fig. 1 illustrates prior art, and

Figs. 2 to 6 illustrate different embodiments of the invention.

Fig. 2 shows, by way of example, a mode of construction of an arrangement in accordance

with the invention revealing the fundamental principle of the invention. It should, furthermore, be remarked that the examples of construction are for a vertical all-around radiating antenna. However, the idea of the invention may also be similarly applied to radiation structures that are otherwise oriented in space. The lowest antenna section is, for instance, so dimensioned that at this end a current loop, i. e., a voltage minimum appears. At this point the outer conductor or inner conductor may be grounded, and in the same way as shown in Fig. 1, the high frequency energy is applied through a transformer *i*. In the interior of the surrounding casing *a* there is situated a further hollow metal tube *k* metallically connected with *a* and insulated from the inner conductor *d*. This tube *k* forms the inner conductor in the following higher situated antenna section *C*, and in the third section *c* it again rests against the inside of the outer tube with which it is metallically connected. In this manner the antenna can be conceived as extended into a suitable number of individual sections. It can be seen that no high frequency field exists in the interior of the tubular line *k*. In accordance with the invention, this line is utilized for carrying the insulated through lines. In accordance with the purpose intended, these electric lines pass at both ends into apparatus which feed or which are fed. Figs. 3 and 4 show embodiments of the general idea of the invention in an improved mode as regards arrangement and construction. In Fig. 3 two straight tubular through lines *k*₁ and *k*₂ are provided. In accordance with the invention, the hollow space of each of the two straight conductors may serve to accommodate therein especially insulated conductor lines.

Fig. 4 shows a construction in which a continuous separate tube *k*₃ is provided, while the two conductors *l* and *m* surrounding each other alternately represent cylindrical pieces insulated from and coaxially arranged to the tube *k*₃.

Figs. 5 and 6 show arrangements, according to the invention, which show that the continuous interior hollow spaces serve for receiving the separate inner conductor connecting the apparatus *n* and *o*.

In practical cases the lowest tube is directly connected to ground or a point of zero radio frequency potential (Fig. 5, point *q*), or across an impedance (Fig. 6 designated by *s*) in accordance with the invention. The length of the lowest section may be chosen equal to a quarter wave

length. In the figures the "ground" is represented as metal plate *t*.

At the other end a metallic body, for instance, in the form of the metal plate *M* is provided 5 in accordance with the invention. The apparatus *o* is thus shielded against the antenna field.

Fig. 6 shows in particular an arrangement, according to the invention, in which two linear antennas are arranged and situated above each 10 other in the same vertical plane. The lower antenna corresponds exactly with the hitherto described arrangement and shows the metallic end plates. The feeding takes place through the high frequency transformer *i*₁. The hollow space *k* 15 contains a further high frequency energy line *v* fed at the bottom through the high frequency transformer *i*₂ and terminating at the top into a second linear antenna *w* having any desired shape. In the arrangement, according to the 20 invention, the lower and upper antenna are effectively decoupled. This degree of decoupling can be increased if the upper metal body is given a large surface. According to the invention, by 25 means of such an antenna two waves differing from each other may be sent out or received.

Furthermore, in accordance with the invention, one of the two antennas may radiate, for instance, through transformer *i*₁ into the lower antenna, and reception may be had by means 30 of high frequency transformer *i*₂ and the upper antenna.

Furthermore, in accordance with the invention, the upper antenna may also enclose an interior space, and may terminate at its upper 35 end into a third antenna. In this case the lowest antenna must enclose two hollow spaces, according to Fig. 3.

We claim:

1. An antenna comprising a plurality of 40 hollow tubular aerial elements arranged end to end substantially in a straight line, a two-conductor transmission line for enabling in-phase excitation of each of said aerial elements, one conductor of said transmission line comprising a 45 hollow tube extending within the hollow spaces of said aerial elements and throughout the length of said antenna, a source of high frequency energy connected to said two-conductor transmission line, another line extending within and 50 throughout the length of said one conductor and insulated therefrom, utilization apparatus at one end of said last line, and a source of energy at the other end of said last line.

2. An antenna comprising several hollow 55 tubular aerial elements arranged end to end substantially in a straight line, a two-conductor transmission line within said elements, each of the conductors of said line connected to alternate elements, one of said conductors comprising a hollow tube and extending throughout the 60 length of said antenna and a transmission line within said tube and insulated therefrom.

3. An antenna comprising several hollow 65 tubular aerial elements arranged end to end substantially in a straight line, a two-conductor

transmission line within said elements, each of the conductors of said line connected to alternate elements, one of said conductors comprising a hollow tube and extending throughout the length of said antenna, a source of high frequency energy connected to said two-conductor transmission line, another line extending within and throughout the length of said one conductor and insulated therefrom, utilization apparatus at one end of said last line, and a source 10 of energy at the other end of said last line. 5

4. An antenna comprising several hollow tubular aerial elements arranged end to end substantially in a straight line, a two-conductor transmission line within said elements, each of the conductors of said line connected to alternate elements, one of said conductors comprising a hollow tube and extending throughout the length of said antenna, a source of high frequency energy connected to said two-conductor 15 transmission line, another line extending within and throughout the length of said one conductor and insulated therefrom, a source of energy at one end of said last line and another antenna at the other end of said last line extending in the same general direction as said first antenna, but resonant to a frequency different from said first antenna. 20 25

5. An antenna comprising several hollow tubular aerial elements arranged end to end substantially in a straight line, a two conductor transmission line within said elements, each of the conductors of said line connected to alternate elements, each of said conductors comprising a hollow tube extending throughout the 30 length of said antenna, a source of high frequency energy connected to said two conductor transmission line, another transmission line extending within and throughout the length of said hollow tubes and insulated therefrom, utilization 35 apparatus at one end of said last mentioned line and a source of energy at the other end of said last mentioned line. 40

6. An antenna comprising several hollow tubular aerial elements arranged end to end substantially in a straight line, a two conductor transmission line within said elements, each of the conductors of said line connected to alternate elements, one of said conductors comprising a hollow tube and extending throughout the 45 length of said antenna, a source of high frequency energy connected to said two conductor transmission line, another line extending within and throughout the length of said one conductor and insulated therefrom, a source of energy at 50 one end of said last line, another antenna at the other end of said last line extending in the same general direction as said first antenna but resonant to a frequency different from said antenna, and a metallic plate between said 55 antennas, said plate being connected to the uppermost end of said hollow tube. 60
